UNITED STATES PATENT OFFICE.

JOHN HARRIS, OF SHEFFIELD, ENGLAND.

MECHANICAL ORE-ROASTING AND LIKE FURNACE.

1,149,754.

Specification of Letters Patent. Patented Aug. 10, 1915.

Application filed November 17, 1911. Serial No. 660,844.

To all whom it may concern:

Be it known that I, JOHN HARRIS, a subject of the King of England, residing in Sheffield, in the county of York, England, have invented certain new and useful Improvements in or Relating to Mechanical Ore-Roasting and like Furnaces, of which the following is a specification.

This invention relates to mechanical ore 10 roasting and like furnaces for use in the generation of gases for the production of fluid acid its object being to prevent the creation of dust within the furnace and to obtain an increased purity and clarity in raw 15 acid produced from the furnace gases.

It is well known that dust arising within the furnace is carried along with the gases evolved therein and is the cause of part of the impurity and of nearly the whole of the 20 discoloration in the raw acid. Various attempts have been made to solve this dust problem but they have not succeeded to any appreciable degree in reducing the discoloration and increasing the purity of the raw 25 acid because they have been directed to the symptoms instead of to the causes of the trouble.

I have found that the greater part if not the whole of the dust causing the discoloration and consequent impurity of the acid is 30 that which arises from that portion of the ore or other material being roasted which is yet in a comparatively cold condition and the main feature of the present invention 35 consists in so treating the charges of ore or like material during the initial stages of the roasting operation that dust pollution of the gases supplied to the acid producing process is eliminated during such initial stages. In 40 the preferred method of effecting this the material is fed to the furnace intermittently and each batch is wholly removed from the delivery area before the next arrives and is then so manipulated that it travels gradually and uniformly along a predetermined path in such manner that partially heated portions are not moved back to mix with colder portions, and the latter do not overtake and mix with parts at a higher temper- 45 ature, for I have found that one of the most fruitful sources of the noxious dust is the promiscuous mixing of material at different temperatures, whether the mixing is effected by feeding the material upon that already 50 in the furnace or whether it takes place sub- sequent to delivery while the material is still

at a temperature substantially below that of its surroundings. The extent of this manipulation will depend upon the nature of the material being roasted, but generally it is 60 advisable to continue it until the material reaches approximately the temperature of its surroundings. Beyond this point any desired means for manipulating the material may be employed. Additional devices tend- 65 ing to reduce the formation of dust may also be employed if desired, such as the employment of sealed discharges, seals around the rabble shaft and by so arranging the gas apertures in relation to the ore openings 70 that the ore does not drop in the path of the draft through the furnace.

The accompanying drawings are diagrammatic of the preferred method of carrying out this invention, Figure 1 representing a 75 sectional elevation of a furnace and Fig. 2 a sectional plan of the first hearth, on the line 2-2 of Fig. 1.

The furnace shown comprises three superimposed roasting chambers A, A¹ and A² 80 and the ore or other material to be roasted is fed intermittently through the feed opening B to the uppermost chamber A by any desired means such as rabble arms A* working upon the roof of the furnace. Each 85 batch of material is then moved gradually and uniformly forward along the desired path by inclined rakes C C¹ on the rabble arm D carried by the shaft E adjacent to which the material falls. It is desirable for 90 each batch of material to be spread also completely around the shaft E, else a portion of the hearth of the chamber will not be utilized. For this purpose the first inclined 95 rake C acting upon each batch of material is of such length and inclination having regard to the quantity of material in each batch that the latter is spread completely around the shaft E by the rake C as well as being moved away from the shaft a distance 100 corresponding to the radius of the circle described by the extreme end of the rake C. Thence the charge is caused to travel gradually and uniformly forward by the inclined rakes C¹ until its temperature is approxi- 105 mately equivalent to that of its surroundings when any desired means of propulsion may be employed such as the plow rakes F.

It will be appreciated that each batch of material will be moved away from the delivery area immediately below the feed opening B by the inclined rake C and that the 110

next batch will be fed upon a clear space out of contact with ore or like material at a higher temperature. When the inclined rake C reaches a newly delivered batch the previous batch has been moved if not entirely beyond the area traversed by this rake at any rate so far from the shaft that the new batch is not mixed therewith. Similarly each of the inclined rakes C¹ leaves a clear space behind it upon which material is moved by the adjacent rake on the shaft side, and so there is no harmful mixing of material at different temperatures.

The path of the outer edge of each of the inclined rakes C¹ coincides with or overlaps that of the adjacent inner edge of the next rake in order to insure that all the ore displaced by one rake comes under the action of the next one and is not left between them to mix with that moved by the first rake at the following revolution.

It will be understood that, as is the general practice in this class of furnace, the floors of the chambers A, A¹ and A² are lined with powdered anthracite, coke or the like. The lining will also form a circular wall around the shaft E co-inciding with the path of the outside edge of the outermost rake carried by the arm D except where this path is overlapped by that of the arm D¹ as shown in Fig. 2. Hence the ore coming under the action of the outermost rake C¹ on the arm D will be limited in its radial movement by this wall which, co-acting with the said outermost rake, will enable the latter to carry the ore around the shaft and to deliver it to the area traversed by the arm D¹ whence it will be moved by the rakes on the arm D¹.

The area traversed by the inclined rake C is preferably raised above the bed of the chamber A in order to decrease the length of fall of material being fed to the furnace and to prevent the possibility of material which has left this inclined rake moving backward to mix with a newly delivered batch. This raised table G may be simply formed with the powdered anthracite, coke or the like which the floors of the chambers are lined by arranging the lower edge of the inclined rake C at the requisite distance above the floor of the chamber. When feeding this lining substance through the furnace initially it will of course fill in the space below the rakes.

The second rabble arm D¹ which acts upon the ore or like material will be provided with inclined rakes C, with plow rakes F or the like or with both according to the substance being treated and its temperature when it reaches the area traversed by this arm.

The gases evolved in the furnace are led to the acid producing process by the flue A³. Any other method of manipulating the

material during the initial stages of the roasting operation so as to feed it gradually and uniformly forward and to keep portions thereof which are at different temperatures from promiscuous admixture may be employed without departing from this invention, and there may be combined therewith additional devices tending to reduce the formation of dust within the furnace. For example, the discharge of the furnace may be sealed by continuing the casing H of the conveyer J substantially beyond the end of the conveyer, thus causing the material to fill completely this extension of the casing before any portion arrives at the outlet H¹. Seals may also be provided in the feed apertures, B, B¹ and B² as indicated by the inclined plates B³ therein, and around the rabble shafts. Such last mentioned seals may be formed by annular plates K surrounding the shafts E and covering the openings in the roasting chamber floors through which the shaft passes. The plates are preferably loose so as to allow of relative movement between the shafts and floors and to prevent damage by any solid body which may accidentally be situated in the path of the rabble arms. In combination with each of these annular plates K an advanced plow, indicated at L, is carried by the rabble arm to move any material being roasted away from the shaft openings in the arched floors and to direct it under the action of the adjacent rabble rakes.

A further arrangement preventing the formation of dust is to dispose the gas apertures M in relation to the feed openings B, B¹ and B² so that the ore does not drop in the path of the draft through the furnace. This may be effected by arranging the gas apertures M at the corners and the feed openings in the center line of the furnace as shown clearly in Fig. 2. Both may, however, be centrally disposed as indicated in the arched floor of the chamber A¹ and in this case the feed opening is situated on that side only of the gas aperture which is opposite to the direction from which the draft through the furnace comes.

What I claim and desire to secure by Letters Patent is:—

1. The herein described method of treating ore in a roasting furnace comprising intermittently feeding charges of ore to the furnace and moving the different batches over the hearth surface therein in such manner that the successive charges are maintained separate throughout the process, whereby mixing of charges having different temperatures is prevented, for the purpose described.

2. The herein described method of treating ore in a roasting furnace comprising intermittently feeding charges of ore to the

furnace and moving the different batches across each of a plurality of hearths and from one hearth to another in such manner that each charge is removed from the delivery area of a hearth prior to the delivery thereon of a following charge, whereby a plurality of successive charges are maintained separate on said initial hearth and throughout the roasting process until they have reached substantially the same temperature, for the purpose described.

3. The herein described method of preventing the formation of dust in the operation of roasting ore in a furnace wherein the ore is moved over a hearth by rabbles on a rotating shaft, comprising intermit-

tently feeding ore onto the hearth adjacent the shaft, the amount of each charge being limited to that which can be displaced at a revolution of the shaft, whereby the delivery 20 area of the hearth will be cleared of each charge before another charge is deposited thereon, and maintaining the successive charges separate while they differ materially in temperature.

In testimony whereof I have signed my name to this specification in the presence of two subscribing witnesses.

JOHN HARRIS.
